UNITED STATES PATENT OFFICE.

ALAMANDER WHITLOW, OF PORT ARTHUR, TEXAS.

FILE-CABINET.

1,149,313.

Specification of Letters Patent. Patented Aug. 10, 1915.

Application filed January 21, 1914. Serial No. 813,429.

To all whom it may concern:

Be it known that I, ALAMANDER WHITLOW, a citizen of the United States, residing at Port Arthur, in the county of Jefferson 5 and State of Texas, have invented a new and useful Improvement in File-Cabinets, of which the following is a specification.

This invention relates to a combination safe and revolving file cabinet, the object of 10 the invention being the safeguarding of the papers placed within the cabinet, both from fire, and damage by water or theft, together with readily operated means for bringing any particular batch of papers or any particular 15 compartment into position where the said papers or the compartment in which papers are to be placed, will be readily accessible.

With these objects in view the invention 20 consists in the novel features of construction hereinafter described, pointed out in the claims and shown in the accompanying drawings, in which—

Figure 1 is a horizontal section, the door 25 of the safe being shown in closed position. Fig. 2 is an enlarged vertical section through a portion of the filing compartments. Fig. 3 is a side elevation of the same portion of the said compartments.

30 In constructing the device I employ a circular safe 1, within which is centrally arranged a vertical rod 2 and rotatably mounted upon said rod is a polygonal casing resting upon the upper end of the rod 2, said 35 rod passing loosely through the bottom of said casing. In the drawings I have illustrated said casing as being octagonal but it may of course have any desired number of sides. Carried upon the exterior face of 40 said casing are a plurality of shelves 4, and I have illustrated said shelves as being arranged in a plurality of tiers and there are of course as many shelves in each tier as there are sides to the casing. Each shelf is 45 provided with vertical end members 5 at right angles to each face of the casing, and between the end members of each side of each shelf works a follower block 6, and as 50 illustrated in Fig. 3 the follower blocks 6 are preferably of a greater height than the said end members. Each shelf is provided midway its ends and upon its upper

side with a transverse groove 7 and bolts 8 work loosely through the faces of the casing 3 and are adapted to slide in the grooves 7 55 of the respective shelves. These bolts are secured as shown in Fig. 3 to the lower edge of the follower blocks 6. Coil springs 9 surround the inner portions of the bolts and tend to pull the follower blocks toward the 60 casing by expansion of said springs, the springs bearing at one end upon the casing and being suitably fixed to the inner end of the bolts or provided with any other suitable form of bearing. Each follower block 65 is provided upon its top with a spring hinged ledge 10 and U-shaped wire clamps 11, one of which incloses the other, are secured to each ledge. These clamps serve the purpose of temporarily holding papers to 70 be placed in the compartment back of the follower block, or they may serve for a temporary holding of papers removed from position back of the block. As said wires are carried by a hinged ledge they may be 75 thrown entirely back out of the way to give ready access to the papers back of the follower block. Each follower block is provided with a suitable knob 12 by means of which it may be drawn outwardly for the 80 purpose of removing or inserting papers.

The entire device above described is carried entirely within the safe 1 and is rotatable therein so that any vertical series of shelves may be brought into alignment 85 with the door opening of said safe. The details of the safe proper do not form a part of this invention and are not claimed.

What I claim is:

1. In a file cabinet having a face member, 90 a shelf arranged thereon, said shelf being transversely grooved, a radially arranged rod working through the face member of said cabinet and adapted to travel in said groove, means for normally drawing said 95 rod inwardly, and a follower block adapted to move transversely across said shelf, said block being secured to said rod.

2. A file cabinet of the kind described comprising a vertical member, a shelf carried by the exterior face of the vertical member, a rod working radially through said vertical member, a coil spring encircling said rod and secured to the inner end 100

of the rod and bearing on the inner face of the vertical member, and a follower block movable transversely across said shelf, said block being connected to the outer end of the rod.

3. In a device of the kind described, a shelf, a follower block movable across the

shelf, a ledge hinged to the upper edge of the block, and spring clamps carried by said ledge.

ALAMANDER WHITLOW.

Witnesses:

W. L. RUTAN,

H. B. TUCKER.
